UNITED STATES PATENT OFFICE.

ALLEN JOHNSTON, OF OTTUMWA, IOWA.

SCREW-MACHINE.

SPECIFICATION forming part of Letters Patent No. 316,788, dated April 28, 1885.

Application filed October 23, 1884. (No model.)

To all whom it may concern:

Be it known that I, ALLEN JOHNSTON, of Ottumwa, in the county of Wapello and State of Iowa, have invented a new and useful Improvement in Screw-Machines, which improvement is fully set forth in the following specification.

This invention relates to machinery for making screws (male and female) and other articles from a long rod or stock by shaping the end of the same, and when necessary screw-threading it, and then cutting off the shaped or shaped and threaded end. Parts of the invention may, however, be useful in machinery for other purposes.

The invention consists, first, in a new arrangement for or mode of bringing the tools successively into action. As common in metal screw-machines, the stock is held in a chuck, and the tools are held in a turret mounted on a slide that moves longitudinally of the machine or parallel to the axis of the chuck; but the said turret, instead of being mounted on an upright axis or axis perpendicular to the plane of the slide's movement, as heretofore, is mounted on an axis parallel to said plane and to the chuck's axis. The tools are thus always parallel to or in line with the chuck's axis, and are not so liable to get out of true as with the ordinary turret. There are also other advantages of a practical nature, which will be readily understood by those skilled in the art.

The invention, secondly, consists in a new arrangement for or mode of revolving the threading-tool in the turret. Heretofore in many machines the die or threading-tool has been revolved sometimes in cutting the thread, (see my Patent No. 241,806, dated May 24, 1881,) and sometimes in unthreading or backing off the die or top. (See my Patent No. 211,742, dated January 28, 1879.) Heretofore, when the threading-tool has been held in a turret, motion has been communicated to the spindle of the threading-tool from a gear or its equivalent outside the turret. In the present improvement a shaft enters the turret axially, and motion is communicated to the tool-spindle through a gear on the end of the said shaft.

The invention, thirdly, consists in mechan-

ism for closing the chuck-jaws by a positive movement. In order to accommodate the small irregularities in the stock or rod held by the jaws a spring is interposed between the parts of the actuating mechanism. Heretofore the jaws have been closed by a spring, which is retracted for opening the jaws.

The invention, fourthly, consists in an arrangement of screws and wedges for closing the jaws with a very powerful pressure.

The invention also comprises certain particular constructions, combinations, and arrangements of parts, as hereinafter more fully set forth.

The accompanying drawings represent a metal screw-machine constructed in accordance with the invention.

Figure 1 is a central vertical longitudinal section of the machine; Fig. 2, a sectional elevation of the chuck-spindle and contained parts; Fig. 3, a front view of the chuck; Fig. 4, a side view of one part of the chuck; Fig. 5, a cross-section on line *u u*, Fig. 2; Fig. 6, a plan of the machine with the upper part removed; Fig. 7, a development on a plane of the cam-drum for bringing the tools into and out of action; Fig. 8, a vertical cross-section on line *x x* of Fig. 1, and in elevation, looking to the left; Fig. 9, an end elevation; Fig. 10, a vertical cross-section on line *y y*, Fig. 1; and Fig. 11, a similar section on line *z z*.

A is the machine-frame; B, a cam-shaft, and C the chuck-spindle. The chuck-spindle is driven by a belt on pulley C'. Motion is conveyed from the gear *b* on the chuck-spindle to the cam-shaft through the gears *b' b''*, loose on the shaft *b'*, gears *b'' b''*, loose on shaft B, gear *b''*, supported in an arc-limb, gears *b'' b''*, fixed on shaft *b''*, and gear *b''*, fixed on shaft B, or by other suitable gearing or mechanical connection.

The chuck is constructed as follows: In the head *c'*, at the inner end of the chuck-spindle, are secured wedges *c''* for forcing in the chuck. These wedges, although they might be made separate, are united to form a ring. This wedge-ring is held from endwise movement by the flange *c''* and the cap *c''*, which fits over the flange. A removable locking-pin, *c''*, that fits in one of the notches in the flange *c''*, prevents it from turning. Inside the wedges or wedge-

ring c^3 are the chuck-jaws c , formed in one piece of spring metal. These are beveled on the outside at the end to correspond with the bevel of the wedges. Behind the chuck-jaws 5 is the follower a , connected with the wedge-ring c^2 by the screw-thread 2, and with the tube c^6 by pins c^1 , tapped into said tube and working in the oblique slots 3 in the follower. By turning the follower in the proper direction (which 10 is effected by pushing in the tube c^6) the screw-thread 2 draws the follower forward, and it in turn pushes forward the chuck-jaws c . As the latter advance, they are forced together by the action of the wedges or wedge-ring c^2 , so 15 as to grasp with great power the rod, blank, or stock inserted between them. When the tube c^6 is drawn out, the follower is turned in the opposite direction and withdrawn, thereby releasing the chuck-jaws, which immediately 20 expand and release the bite upon the rod, blank, or screw-stock. The tube c^6 is moved in and out by the feed or chuck cam E, and is prevented from turning independently of the 25 chuck-spindle by the splines s .

25 The device a' , through which the motion is conveyed, has a pin, 4, that enters the groove 5 of the cam E, and an arm, 6, whose upper end projects between the nuts a^2 a^3 on the tube c^6 . A spring, F, is interposed between the 30 arm 6 and the nut a^3 . It is shown as a strong spiral compression-spring. Its effect is to compensate for any inequalities in the size of the rod, blank, or screw stock. The device a' , as shown, slides on the stud a^4 , which is screwed 35 into the machine-frame.

The groove 5 could extend all the way around the cam E; but practically this is not required, as when the chuck-jaws are compressed the friction (owing to the small pitch 40 of thread 2) is sufficient to prevent their expanding.

The chuck can be adjusted at both ends of the chuck-spindle. For adjusting at the inner end it is only necessary to remove the locking-pin 45 c^5 and turn the wedge-ring c^2 in the proper direction. The screw-thread 2 then moves the follower back or forward (as the case may be) and compresses the chuck-jaws or allows them to expand a corresponding distance. The locking-pin is then replaced. For adjusting at the outer end the nuts a^2 a^3 are screwed more or less on or off the tube c^6 .

The tool-holding turret G is mounted on the longitudinal slide H on an axis parallel with 55 that of the chuck. It is inclosed in the head a on the slide, which constitutes at once a bearing and a cover or housing. A journal or stud, g , projecting rearward, carries a gear, g' , which engages the gear or toothed wheel I, provided 60 on the back face with projecting pins i for shifting the turret step by step. The stud or journal g passes through the standard h' on the slide H. The shifting-wheel I turns on a stud, h^2 , screwed into said standard. The shifting-wheel could, of course, be fixed upon the 65 journal g , the gear g' being omitted. Under

the overhanging tail h^3 of the slide H is a notched cross-slide, K, set in a groove in the machine-frame. The longitudinal slide is reciprocated by the cam-drum L through the 70 pin h^4 , which projects into the cam-groove l on the periphery of said drum. When the slide is drawn back, (to the right in Fig. 1,) the lowermost pins, i , enter the notch k in cross-slide K. While the longitudinal slide remains back the cross-slide is moved (to the left, as shown in Fig. 8) so as to turn the wheel I, gear g' , and turret G the proper distance to bring the next tool in line with the chuck. A slot, k' , is made in the cross-slide, and as 80 the wheel I turns one of the pins enters the slot. When the longitudinal slide is moved forward, the pins i are drawn out of the notch k and slot k' in the cross-slide, and the latter is returned to its original position. 85 (Shown in Fig. 6.) The cross-slide K is reciprocated by the bent lever K', pivoted at k' to the machine-frame, connected with the slide K at k^3 by a slot and pin, and operated by the cam-drum L, a pin, k^4 , on the lever projecting 90 into the irregular groove l' on the periphery of the drum. The turret is prevented from turning when the longitudinal slide is moved forward to bring the tools into action by the device m^* , fixed to the machine-frame and 95 constituting a projection, which enters one of the notches 7 on the locking-plate Q, screwed or otherwise fastened to the turret.

The tools are held in the ordinary or any suitable way in the turret. As shown, the 100 turret is provided with four tool-holes, one containing the threading-tool, another being for a length-gage, and the two others for shaping-tools—such as a box tool, drill, turning-down tool, and the like.

The threading-tool consists of a cylindrical shell, M, a cap, m , a non-rotating clutch-piece, m' , the rotating clutch-piece m^2 , the gear m^3 , fast on the clutch-piece m^2 , the spindle m^4 , the clutch-piece m^5 , fast on the spindle, and the thread-cutter m^6 . (Shown as a die, but it could be a tap as well.) Motion is communicated from the gear n on the chuck-spindle through the gear n' the shaft n^2 , (which extends axially into the turret,) the 110 gear n^3 , and gear m^3 to the clutch-piece m^2 . While the die or thread-cutter is in action, the clutch-piece m^5 is engaged by the clutch-piece m^2 , and the die or thread cutter is rotated in the same direction as the chuck, but at a greater 115 speed. After the thread has been cut the die m^6 , spindle m^4 , and clutch-piece m^5 are held from endwise movement, while the slide H, and with it the clutch-pieces m^2 and m^5 , is drawn back. The clutch-piece m^5 is thus disengaged from the rotating clutch-piece and engages the non-rotating clutch-piece m' , whereupon the die or cutter m^6 , being held stationary, the continued rotation of the chuck releases it from the newly-cut thread. The 120 clutch-piece m' is prevented from rotating by the screw m^8 , whose head fits in the slot m^9 in

the case M. A spiral compression-spring, m^{10} , is interposed between clutch-piece m' and cap m .

The cutting-off tool N is mounted on a cross-slide, n , movable in ways of the machine-frame, and is operated through the bent lever P, pivoted to the machine-frame, connected at one end with the cross-slide n , and provided at the other end with a pin that projects into the groove l^2 in the periphery of cam-drum L. The weight W for advancing the rod or stock is supported in the bight of cord w , one end of which is held by the supporting-bar w' , and the other is connected with a slide or pusher-back of the rod or screw stock. The arrangement shown is the same as in my Patent No. 293,176, February 5, 1884.

The operation of the machine will be readily understood. The rod or screw-stock is introduced through the chuck-spindle and between the chuck-jaws, as usual. Suppose that a screw, a nut, or other article has just been severed from the rod or screw-stock and that the cutting-off tool has been withdrawn. At this point the length-gage has been brought opposite the chuck and the longitudinal slide and turret have been moved forward, so that the pins i of the shifting-wheel I are clear of the cross-slide K. So soon as the cutting-off tool is out of the way, the cam E draws back the tube c^6 and releases the chuck-jaws e , whereupon the weight W urges forward the rod or screw-stock until it strikes the length-gage. The cam E then advances the tube c^6 , turning the follower a , and causing the chuck-jaws to resume their hold upon the rod or screw-stock. During this time the cross-slide K has been returned to the position shown in Fig. 9. When the chuck has resumed its hold upon the rod or stock, the longitudinal slide is drawn back, the cross-slide is moved to turn the turret so as to bring one of the shaping-tools into position, and the longitudinal slide is then advanced. When the slide is moved forward, the cross-slide K is returned. After the shaping-tool has cut as far as desired the longitudinal slide is returned, the cross-slide is shifted, turning the turret and bringing the next tool in line with the chuck. The longitudinal slide is now again advanced, the cross-slide is returned, the longitudinal slide is drawn back, and the cross-slide is shifted, bringing the threading-tool in line with the chuck. The longitudinal slide is then advanced and returned, the cross-slide being returned while the turret is forward. During the thread-cutting the cutting-off tool is brought into action; but it does not completely sever the rod until the thread-cutter has been released from the newly-cut thread. During the last of the cutting-off tool's action and the return of the said tool the turret is turned to bring the length-gage into line with the chuck, and the longitudinal slide is advanced the proper distance to bring the length-gage into position to measure the rod when fed forward.

The machine herein described is more particularly designed to make thumb-nuts and long screws and such articles as cannot readily be made with the machine described in my Patent No. 299,477, dated May 27, 1884.

It is evident that modifications can be made in details without departing from the spirit of the invention, and that parts of the invention may be used separately. For example, the tube in my Letters Patent of 1881 and 1884, before referred to, which is arranged inside the chuck-spindle and is moved endwise to release and restore the bite of the chuck-jaws, could be operated by the mechanism herein described for operating the tube c^6 ; also, the tube c^6 herein could be operated as is the tube in the said patents.

Having now fully described my said invention and the manner of carrying the same into effect, what I claim is—

1. The combination, with the chuck, of the longitudinal slide and the tool-holding turret mounted on an axis parallel with that of the chuck, and the automatic mechanism for revolving said turret to bring the tools successively in line with the said chuck, substantially as described.

2. The combination, with a turret and a threading-tool carried by said turret, of the axial gear and the mechanism operated thereby for revolving the said threading-tool, substantially as described.

3. The combination of the chuck, the longitudinal slide, the tool-holding turret mounted on an axis parallel with that of the chuck, the threading-tool, and the gears for revolving said tool, substantially as described.

4. The combination, with the longitudinal slide and the tool-holding turret mounted on a horizontal axis on said slide, of the locking-plate and projection for holding the turret stationary when the slide is moved forward to bring the tools into action, substantially as described.

5. The combination, with the longitudinal slide and the tool-holding turret mounted thereon, of the cross-slide and the shifting-wheel for turning said turret, substantially as described.

6. The combination, with the chuck and the mechanism for opening and closing the chuck-jaws to permit the rod or long stock to be fed forward, of the longitudinal slide, the cam and connections for reciprocating the same, the tool-holding turret mounted on a horizontal axis on said slide, and the mechanism for turning the turret step by step, substantially as described.

7. In a chuck, the combination, with the chuck-jaws, of the cam and connections for closing said jaws by a positive movement by means of a screw, substantially as described.

8. The combination, with the chuck-jaws, of the cam and connections for releasing and for closing said jaws both by the positive action of said cam, substantially as described.

9. The combination, with the chuck-jaws, of the cam, the rigid metal pieces, and the interposed spring for operating the chuck-jaws, the pressure in closing the jaws being communicated through said spring, substantially as described.

10. The combination, with the chuck-jaws and mechanism for opening and closing the same, of the adjusting devices at the inner 10 end of the chuck-spindle for regulating the bite of the jaws, substantially as described.

11. The combination, with the chuck-spindle and the chuck-jaws, of the feed or chuck cam, the device acted upon by said cam, the 15 tube inside the spindle, the spring interposed between the said device and the said tube, and the devices actuated by the tube to close said jaws, substantially as described.

12. The combination, with the adjustable 20 wedges secured to the chuck-head, of the chuck-jaws movable longitudinally with respect to said wedges, substantially as described.

13. The combination, with the wedges unit- 25 ed to form a ring, of the inclosed chuck-jaws formed in one piece of metal, said jaws being beveled on the outside at the ends to correspond with the wedges, and being movable by means of a screw with respect to said wedges, 30 substantially as described.

14. In a chuck, the combination, with the head, the wedges, and the chuck-jaw, of the screw-follower and the tube connected with 35 said follower by a pin working in an oblique slot, substantially as described.

15. In a chuck, the combination, with the tube for operating the chuck-jaws and the nuts on the outer end of the tube, of the device

for communicating motion to said tube and the spring interposed between said device and 40 one of said nuts, substantially as described.

16. In a chuck, the combination, with the head, the ring therein, the follower connected with said ring by a screw-thread, and the tube connected with said follower by a pin work- 45 ing in an oblique slot, of the notched flange and locking-pin for adjusting the said ring in said head, substantially as described.

17. The combination of the chuck-head, the wedges, the chuck-jaws, and the screw-fol- 50 lower, substantially as described, so that the jaws are compressed automatically by the combined action of the screw and wedges, as set forth.

18. The combination, in a chuck, with the 55 chuck-jaws and screw-follower, of the adjustable ring engaging the thread on said follower, substantially as described.

19. In a chuck, the combination, with the head, the ring, the follower connected with 60 said ring by a screw-thread, and the tube so connected with the follower as to revolve the follower by its reciprocating motion, substantially as described.

20. In a chuck, the combination, with the 65 head, the ring therein, and the follower connected with said ring by a screw-thread, substantially as described.

In testimony whereof I have signed this specification in the presence of two subscri- 70 ing witnesses.

ALLEN JOHNSTON.
